United States Patent Office

Des. 190,717
Patented June 27, 1961

190,717

CAP

Lillian Gettinger, Baltimore, Md., assignor to Andre
Fantasies, Inc., a corporation of Maryland

Filed Aug. 26, 1960, Ser. No. 61,907

Term of patent 14 years

(Cl. D3—13)

FIG. 1—1

I claim:

The ornamental design for a cap, substantially as shown.
